A. C. FINNEY

CIRCUIT CONTROL SYSTEM

Filed Feb. 2, 1923

Inventor :
Alfred C. Finney

by Alexander S. Scott.
His Attorney

UNITED STATES PATENT OFFICE.

ALFRED C. FINNEY, OF SCHENECTADY, NEW YORK, ASSIGNOR TO GENERAL ELECTRIC COMPANY, A CORPORATION OF NEW YORK.

CIRCUIT-CONTROL SYSTEM.

Application filed February 2, 1923. Serial No. 616,457.

To all whom it may concern:

Be it known that I, ALFRED C. FINNEY, a citizen of the United States, residing at Schenectady, in the county of Schenectady, 5 State of New York, have invented certain new and useful Improvements in Circuit-Control Systems, of which the following is a specification.

My invention relates to improvements in 10 circuit control systems and more particularly to circuit control systems for a plurality of electric conductors arranged to be controlled by a plurality of electric switches so that the opening of any switch will effect the 15 simultaneous opening of all the switches and so that each of the switches can be independently closed. An object of my invention is to provide for a plurality of electric conductors, an improved system of 20 circuit control in which each of a plurality of conductors may be controlled by an electric switch of the type arranged to be controlled and actuated electrically for opening and closing without materially modifying the 25 construction of the switch and without regard to the fault responsive control thereof, so that the opening of any switch will effect the simultaneous opening of all the switches and so that each of the switches can be 30 independently closed.

My invention will be better understood from the following description taken in connection with the accompanying drawing and its scope will be pointed out in the appended 35 claims.

In the single figure of the accompanying drawing, I have illustrated diagrammatically an embodiment of my invention in a circuit control system comprising a plurality of electric conductors 1, 2, each of 40 which may be arranged to be controlled by suitable electric switches or circuit interrupting means, such as circuit breakers 3, 4 respectively, arranged so that the opening 45 of any circuit breaker will effect the substantially simultaneous opening of all and so that each circuit breaker can be independently closed. The conductors 1, 2 may be, for example, the outside wires of an Edison 50 three-wire direct current system for the control of which my invention is particularly advantageous, or they may represent, for example, the circuits on the high and low tension sides of a power transformer. It is, 55 however, distinctly to be understood that my

invention is not limited to these particular applications, but may be used to advantage in any system comprising a plurality of conductors whose circuits it is desired to open simultaneously and close independently. The circuit breakers 3, 4 may be of the type arranged to be controlled and actuated electrically independently of circuit 60 conditions and may also be provided with any of the well known fault-responsive means for control in response to abnormal 65 circuit conditions, such as over-current, under-voltage, etc., since in accordance with my invention the circuit breakers are free for any fault-responsive control desired. 70 For controlling and actuating the circuit breakers 3, 4 electrically, they may be provided with any suitable control means such as opening coils 5, 6 respectively, arranged to effect the release of latching members 7 75 and 8 respectively, and also with suitable actuating or closing means such as closing coils 9 and 10 respectively. For controlling the circuit breakers 3, 4 in response to abnormal circuit conditions, they may be provided with any suitable electroresponsive devices such as over-current trip coils 11 and 12 respectively, arranged to effect the release of the latching members 7 and 8 respectively, and suitable means operative in 80 response to other abnormal conditions as is well known to the art.

The opening coils 5 and 6 and the closing coils 9 and 10 may be energized from any suitable source, such as control buses 13 and 90 14 and are arranged to have their circuits controlled by any suitable means such as control switches 15 and 16 arranged to control the circuits of the opening coils 5 and 6 respectively, and control switches 17 and 18 95 arranged to control the circuits of the closing coils 9 and 10 respectively. For indicating the positions of the circuit breakers 3 and 4, suitable indicating means, such as green lamps 19 and 20 may be provided to 100 indicate circuit open position and red lamps 21 and 22 to indicate circuit closed position. The various control circuits may also be provided with suitable protective means such as fuses 23 and resistors 24 if necessary. 105

For controlling the indicating lamps 19, 20, 21 and 22 and also for completing interlocking circuits for the control means or opening coils 5 and 6 so that, in accordance with my invention, the opening of any cir- 110

cuit breaker will effect the opening of the other or others, each of the circuit breakers 3 and 4 may be provided with auxiliary switching members 25, 27 and 26, 28 respectively. The switching member 25 is arranged to close contacts 29 in the control circuit of the lamp 21 when the circuit breaker 3 is closed and to close contacts 31 in the control circuit of lamp 19 when the circuit breaker 3 is open. Similarly the switching member 26 associated with the circuit breaker 4 controls contacts 30 and 32 in the control circuits of lamps 22 and 20 respectively.

15 In order that the opening of one circuit breaker may, in accordance with my invention, effect the simultaneous opening of the other or others, the switching members 27 and 28, which are open when the respective 20 circuit breaker is closed and closed when the respective circuit breaker is open, are arranged to control contacts 33 and 34 in interlocking circuits comprising conductors 36 and 35 respectively so as to complete the 25 interlocking circuit of the control means 6 or 5 of one circuit breaker upon the opening of any other circuit breaker as will be more clearly set forth in the description of the operation of my invention. Furthermore, 30 more, in order that each circuit breaker may be independently closed without being immediately tripped open by its opening coil, I provide means arranged to be controlled by the closing means of any circuit breaker to render the control means or opening coil thereof inoperative to open the same until another circuit breaker has been closed. This means may be operative in 35 response to the closing of the control circuit 40 of the closing coil of the circuit breaker and may comprise suitable electro-responsive devices or relays 37, 38 having contact controlling members 39 and 40 respectively, arranged to control contacts 41 and 42 respectively, in the interlocking circuits comprising conductors 35 and 36. The relays 37 and 38 may be normally deenergized so that contacts 41 and 42 are normally closed, but upon the closing of one of the control 45 switches 17 or 18, the corresponding relay 37 or 38 will be energized to open contacts 41 or 42 in the interlocking circuits comprising conductors 35 or 36, thus rendering the control means 5 or 6 of circuit breaker 3 or 4 inoperative. Each of the 50 relays 37, 38 may be arranged when energized to seal itself in through contacts 43 and 44 controlled by contact controlling members 45 and 46 respectively so as to 55 maintain the interlocking circuits open until the respective circuit breaker is closed. The closing of one of the control switches 17 or 18 energizes a relay 47 or 48 arranged to complete the circuit of the closing coil 60 9 or 10 respectively. The relays 47, 48

through contact controlling members 49, 50 control contacts 51, 52 respectively in the circuits of the closing coils 9 and 10, and are preferably of the instantaneous closing, time delay opening type so as to insure that the closing coil remains energized until the circuit breaker is definitely closed.

Assuming now that the circuit breakers 3, 4 are in the circuit closed position as shown in the accompanying drawing, the operation of the illustrated embodiment of my invention is as follows:—The opening of each of the circuit breakers may be effected in each of two ways, that is to say by the operation of the fault-responsive means associated with the circuit breaker and also the opening coil associated with the circuit breaker. Considering either of the circuit breakers 3, 4, for example, circuit breaker 3, over-current in conductor 1 will energize the over-current fault-responsive means 11 to effect the release of latching member 7, or, if control switch 15 is closed, the opening coil 5 will be energized to effect the release of latching member 7. The control circuit of the opening coil 5 is bus 14, conductor 53, control switch 15, conductor 55, opening coil 5, contacts 29, switching member 25, conductor 57 and bus 13. Upon the opening of the circuit breaker 3, switching member 25 opens contacts 29, thereby interrupting the indicating lamp control circuit comprising bus 14, conductor 53, lamp 21, conductor 59, contacts 29, switching member 25, conductor 57 and bus 13, and closes contacts 31 thereby completing the indicating lamp control circuit comprising bus 13, conductor 61, lamp 19, conductor 63, contacts 31, switching member 25, conductor 65 and bus 14. Also upon the opening of circuit breaker 3, switching member 27 closes contacts 33, thereby completing the interlocking circuit of the opening coil 6 of the circuit breaker 4, as follows: bus 14, conductor 65, contacts 33, switching member 27, conductor 36, contacts 42, contact controlling member 40, conductor 56, opening coil 6, contacts 30, switching member 26, conductor 58 and bus 13. Consequently, the opening of circuit breaker 4 occurs substantially simultaneously with the opening of circuit breaker 3. Upon the opening of circuit breaker 4, switching member 26 opens contacts 30, thereby opening the indicating lamp control circuit comprising bus 14, conductor 54, lamp 22, conductor 60, contacts 30, switching member 26, conductor 58 and bus 13, and closes contacts 32, thereby completing the indicating lamp control circuit comprising bus 13, conductor 62, lamp 20, conductor 64, contacts 32, switching member 26, conductor 66 and bus 14. At the same time, switching member 28 closes contacts 34 in the interlocking circuit of the opening coil 5 of the circuit breaker 3, the

circuit being as follows: bus 14, conductor 66, contacts 34, switching member 28, conductor 35, contacts 41, contact controlling member 39, conductor 55, opening coil 5, 5 contacts 29 and switching member 25, if the circuit breaker 3 be closed, conductor 57 and bus 13.

breaker 4, switching member 26 opens contacts 34 thereby opening the energizing circuit of relay 37 which returns to its normal or interlocking position, that is, with contact controlling member 39 closing contacts 41. Upon closing control switch 18 relay 38 will not be energized since its energizing circuit is open at contacts 33 when the circuit breaker 3 is closed. It is therefore obvious that if any one of the circuit breakers alone is closed on a faulty circuit, it will be opened immediately by its fault-responsive means and, if one circuit breaker is closed on a sound line and the remaining circuit breaker is closed on a faulty line or a fault occurs on any line at any time or any breaker is opened by its control means, all of the breakers will be opened substantially simultaneously in consequence of the interlocking of the opening coils. The operation of closing circuit breaker 4 first and then the remaining circuit breaker or breakers will be obvious by analogy with the operation of closing circuit breaker 3 first, as herein set forth. In the application of my invention to the outside wires of an Edison three-wire direct current system, if one circuit breaker is closed and then the second circuit breaker is closed on a faulty circuit, the circuit breaker closed first is stationary and will open more quickly than the last closed circuit breaker, since the mechanism of the circuit breaker first closed has merely to be accelerated from a standstill and not decelerated, stopped and accelerated as does the mechanism of the last closed circuit breaker which completes the faulty circuit. Moreover, each circuit breaker may be closed independently without the necessity of closing all so that any circuit can be placed in operation alone without affecting either the control of the circuit breaker by any of the fault responsive means associated therewith or the electric control and actuation of the circuit breaker. Thus in accordance with my invention any electrically controlled and actuated circuit breaker equipped with any desired fault responsive means may be employed, as the changes in construction necessary to adapt the circuit breaker to my invention are substantially immaterial, inasmuch as they embody merely the equipping of the circuit breaker with suitable auxiliary switching means.

Although I have shown and described my invention in considerable detail, I do not wish to be limited to the specific details thereof, as shown and described, but may use such modifications, substitutions, or equivalents thereof, as are embraced within the spirit of my invention. 120 125

What I claim as new and desire to secure by Letters Patent of the United States, is:

1. A circuit control system of the class described comprising a plurality of con-

ductors, a plurality of electric switches arranged one in each of a plurality of said conductors and adapted to be operated to control the circuits thereof, control means 5 operative in response to the opening of one of said switches to effect the opening of another thereof, means adapted to be operated to close said other switch, and means arranged to be controlled by said closing 10 means to render said control means inoperative until the closing of said one of said switches.

2. A circuit control system for a plurality of electric conductors comprising a plurality 15 of circuit interrupting means adapted to be operated to control the circuits of said conductors, control means for opening said circuit interrupting means, means operative in response to the opening of one of said circuit interrupting means to effect the opening of another of said circuit interrupting means by the control means thereof, means for closing said circuit interrupting means, and means arranged to be controlled by said 20 closing means to render the control means of one of said circuit interrupting means inoperative until the closing of another of said circuit interrupting means.

3. A circuit control system of the class 30 described comprising a plurality of conductors, a plurality of electric switches arranged one in each of a plurality of said conductors and adapted to be operated to control the circuits thereof, control means for 35 opening one of said switches, means arranged upon the opening of another of said switches to render said control means operative, means adapted to be operated to close said one of said switches, and means arranged 40 to be controlled by said closing means to render said control means inoperative until the closing of said other switch.

4. A circuit control system of the class 45 described comprising a plurality of conductors, a plurality of electric switches arranged one in each of a plurality of said conductors and adapted to be operated to control the circuits thereof, control means for opening each of said switches, means arranged upon the opening of one of said switches to complete the circuit of the control means of another of said switches to effect the opening thereof, means adapted to be operated to close each of said switches 50 independently of the other, and means arranged to be controlled by said closing means to render the control means of one of said switches inoperative to open the same until the closing of another of said switches.

5. A circuit control system of the class 60 described comprising a plurality of conductors, a plurality of electric switches arranged one in each of a plurality of said conductors and adapted to be operated to control the circuits thereof, means comprising

ing an opening coil associated with each of said switches for effecting the opening thereof, means arranged upon the opening of one of said switches to complete the circuit of the opening coil of another of said switches whereby to effect the opening thereof, means comprising a closing coil associated with each of said switches for effecting the closing of each thereof independently of the other, and electroresponsive means arranged to be controlled by said closing means to open the circuit of the opening coil of one of said switches and maintain said circuit open until the closing of another of said switches. 80

6. A circuit control system of the class described comprising a plurality of conductors, a plurality of electric switches arranged one in each of a plurality of said conductors and adapted to be operated to control the circuits thereof, means comprising an opening coil associated with one of said switches for effecting the opening thereof, an interlocking circuit for said opening coil, means arranged upon the opening of another of said switches to complete said interlocking circuit thereby to energize said opening coil and effect the opening of the switch associated therewith, closing means comprising a closing coil associated with said other switch for effecting the closing thereof, and electroresponsive means arranged to be controlled by said closing means to open said interlocking circuit and maintain the same open until the closing of said other switch. 95

7. A circuit control system of the class described comprising a plurality of conductors, a plurality of electric switches arranged one in each of a plurality of said conductors and adapted to be operated to control the circuits thereof, means comprising an opening coil associated with one of said switches for effecting the opening thereof, a normally open interlocking circuit for said opening coil, means arranged upon the opening of another of said switches to complete said interlocking circuit thereby to energize said opening coil and effect the opening of the switch associated therewith, a closing coil associated with said other switch for effecting the closing thereof, control means adapted to be operated to control the circuit of said closing coil, and electroresponsive means arranged to be controlled by said control means to open said interlocking circuit and maintain the same open until the closing of said other switch. 110

8. A circuit control system of the class described comprising a plurality of conductors, a plurality of electric switches arranged one in each of a plurality of said conductors and adapted to be operated to control the circuits thereof, an opening coil 115 associated with each of said switches and

arranged when energized to effect the opening thereof, a normally open interlocking circuit for each of said opening coils, auxiliary switching means associated with each 5 of said switches and arranged upon the opening of one of said switches to complete the interlocking circuit of the opening coil of another of said switches to effect the opening thereof, means for closing each of 10 said switches, means comprising a plurality of control switches for controlling said clos-

ing means whereby each of said switches may be closed independently, and relay means for controlling said interlocking circuits arranged to be controlled by said control switches to render the opening coil of one of said switches inoperative to open the same until the closing of another of said switches. 15

In witness whereof I have hereunto set 20
my hand this 31st day of January, 1923.

ALFRED C. FINNEY.
